FASTENER FOR SANITARY NAPKINS AND
THE LIKE

Ludwig Stark, North Bergen, N. J.

Application May 20, 1936, Serial No. 80,698

7 Claims. (Cl. 24—73)

This invention relates to new and useful improvements in a fastener for sanitary napkins and the like.

The invention has for an object the construction of a holder which is characterized by a flat body having an opening for a supporting element and a pair of adjacent openings separated by a transverse bar element, and a gripper member associated with the body in a novel fashion.

10 Still further the invention proposes mounting the gripper element on one side of the body and extendible over the bar element and adapted to clamp the end of the napkin against the bar element.

15 Still further the invention proposes the provision of a latch element mounted on the other side of the body and coactable with said gripper member to hold it in proper position.

Another one of the objects of this invention is a construction which permits the gripper member to be removed and replaced so that the holder may be adapted to hold the ends of napkins which are of slightly different thicknesses.

20 Another object of the invention is the construction of a device as mentioned which is simple and durable and which may be manufactured and sold at a reasonable cost.

25 For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

30 Fig. 1 is a perspective view of a holder associated with a sanitary napkin constructed according to this invention.

35 Fig. 2 is a fragmentary sectional view taken on the line 2—2 of Fig. 1.

40 Fig. 3 is an elevational view of the holder per se.

45 Fig. 4 is a sectional view taken on the line 4—4 of Fig. 3.

Fig. 5 is a perspective view of the holder per se.

50 Fig. 6 is a view similar to Fig. 5, but illustrating a modification of the invention.

Fig. 7 is a sectional view taken on the line 7—7 of Fig. 6.

55 Fig. 8 is a fragmentary plan view of Fig. 6.

Fig. 9 is a fragmentary sectional view similar to Fig. 2, illustrating another use of the device.

The holder for sanitary napkins comprises identical devices adapted to hold the ends of a napkin. Each of the devices comprises a flat

body 10 having an opening 11 at one end for a supporting element 12. This flat body is also provided with a pair of adjacent openings 13 and 14 which are separated by a transverse bar element 15. A gripper member 16 is hingedly mounted 5 on one side of the body and is extendible over the bar element. A latch element 17 is mounted on the other side of the body and is coactable with the gripper element.

The flat body 10 is formed from a sheet of 10 stiff material such as composition material or metal. The supporting element 12 comprises a strip of material which may be connected with one's foundation garment or other support, the lower end of which is engaged through the opening 11 to form a loop 12'. Several stitches 18 are engaged through the bar end of the supporting element 12 to maintain the loop construction. The transverse bar 15 is integral with the material of the body 10. At its ends 15' it is 20 slightly bent downwards (see particularly Fig. 2) so as to increase the space between the gripping member 15 and the bar. The amount to which this transverse bar is bent downwards depends merely upon the thickness of the end of the napkin with which the device is intended to be used. 25

The gripper element 16 comprises a strip of material which has edge portions 16^a bent downwards and formed with teeth or serrations. At one end the gripper member 16 is forked and the fingers 16^b of the fork are bent around the side portion of the body 10 so as to straddle the transverse bar element 15. Thus the gripper element is hingedly mounted, while at the same time it is restrained from moving longitudinally. The outer end of the gripper member is formed with a curved portion 16^c which is adapted to rest against the outer edge of the body 10 remote from the hinge side. 35

The latch element 17 is formed from a small 40 piece of sheet material which is forked at its inner end and the fingers 17^a of which are bent around the side portion of the body 10 so that the latch element is pivotally supported. This latch element is adapted to engage over the free 45 end 16^c of the gripper member in a manner so that this free end passes through the opening between the junctions of the fingers 17^a of the latch element. This is clearly shown in Fig. 4. Thus, the latch element holds the gripper member in fixed position. 50

In Figs. 6-8 inclusive a modified form of the invention has been disclosed which is very similar to the previous form, distinguishing merely in the fact that it is provided with a transverse 55

bar element 15^c which is removable and replaceable. The parts which correspond to the identical parts in the previously described form of the invention may be recognized by the identical reference numerals. It should be noted that the side portions of the body 10 at the area where the transverse bar element 15^c is located is formed with recessed portions 10^c. The ends of the transverse bar element 15^c are turned around 10 the reduced side portions of the body 10 so that the resiliency of the material maintains the position of the bar element. At the same time the recesses 10^c prohibit the bar element from sliding along upon the body 10. This transverse bar element 15^c has a central portion depressed to a pre-determined amount, as for example, the amount shown in Fig. 7. When it is desired to adapt the holder to napkins having thicker or thinner end portions it is merely necessary to 20 remove the transverse bar element 15^c and to replace it with a bar element having a central depressed portion of the desired depth.

The operation of the device is as follows: A sanitary napkin 20 may be quickly supported at 25 its ends upon the holders in the following manner. The latch element 17 and the gripper member 16 must first be swung open to the position shown in Fig. 5. Then the end 20^a of the napkin is engaged upwards through the opening 30 11 and across the transverse bar element 15. The gripper member 16 is pivoted downwards against the end 20^a and the latch element 17 is pivoted over the free end of the gripper member to latch it in position.

35 In Fig. 9 the supporting strip 12' is wound around the flat body 10 and the end 20^a of the napkin is placed on top of the covered holder and thereafter locked in position by members 16 and 17, as previously described.

40 While I have illustrated and described the preferred embodiments of my invention, it is to be understood that I do not limit myself to the precise constructions herein disclosed and the right is reserved to all changes and modifications 45 coming within the scope of the invention as defined in the appended claims.

Having thus described my invention, what I claim as new, and desire to secure by United States Letters Patent is:—

50 1. A fastener for sanitary napkins and the like, comprising a flat body having an opening for a supporting element and a pair of adjacent openings separated by a transverse removable bar element adapted to engage recesses in the sides 55 of said body to prevent said member from moving laterally, a gripper member hingedly mounted on one side of said body and extendible over said bar element, and a latch element mounted on the other side of said body and coactable with 60 said gripper member, said removable element allowing different sized napkins to be used.

65 2. A fastener for sanitary napkins and the like, comprising a flat body having an opening for a supporting element and a pair of adjacent openings separated by a transverse removable bar element adapted to engage recesses in the sides 70 of said body to prevent said member from moving laterally, a gripper member hingedly mounted on one side of said body and extendible over said bar element, and a latch element mounted on the other side of said body and coactable with 75 said gripper member said removable element allowing different sized napkins to be used, said flat body comprising sheet material stamped with said openings.

3. A fastener for sanitary napkins and the like, comprising a flat body having an opening for a supporting element and a pair of adjacent openings separated by a transverse bar element, a gripper member hingedly mounted on one side 5 of said body and extendible over said bar element, and a latch element mounted on the other side of said body and coactable with said gripper member, said gripper member comprising a strip of material formed at one end with a fork construction, the fingers of which engage around the side portion of said body so as to straddle the end of the transverse bar element, the side portions of said gripper member being bent downwards and formed with serrations, and the free 10 end being provided with a portion adapted to partially encircle the remote side of the flat body.

4. A fastener for sanitary napkins and the like, comprising a flat body having an opening for a supporting element and a pair of adjacent openings separated by a transverse bar element, a gripper member hingedly mounted on one side of 20 said body and extendible over said bar element, and a latch element mounted on the other side of said body and coactable with said gripper member, said latch element comprising a small sheet of material, one end of which is formed with a fork construction the fingers of which encircle the side of said flat body straddling the end of the transverse bar, said latch element being adapted 30 to pivot over the end of the gripper member so that the end of the gripper member passes through the junction of said fingers.

5. A fastener for sanitary napkins and the like, comprising a flat body having an opening for a 35 supporting element and an adjacent opening, a removable and replaceable transverse bar extending across said latter-mentioned opening and having its ends removably engaging the sides of said body, a gripper member hingedly 40 mounted on one side of said body and extendible over said bar element, and a latch element mounted on the other side of said body and coactable with said gripper member, said transverse bar element having its ends partially turned 45 around the side portions of said body and resiliently maintaining itself upon the body.

6. A fastener for sanitary napkins and the like, comprising a flat body having an opening for a 50 supporting element and an adjacent opening, a removable and replaceable transverse bar extending across said latter-mentioned opening and having its ends removably engaging the sides of 55 said body, a gripper member hingedly mounted on one side of said body and extendible over said bar element, and a latch element mounted on the other side of said body and coactable with said gripper member, said transverse bar element having its ends partially turned around 60 the side portions of said body and resiliently maintaining itself upon the body, the inner ends of said gripper member and said latch element being formed with forked portions the fingers of which encircle the sides of the flat body and straddle the ends of said transverse bar element.

7. A fastener for sanitary napkins and the like, comprising a flat body having an opening for a supporting element and an adjacent opening, a removable and replaceable transverse bar extending across said latter-mentioned opening and having 70 its ends removably engaging the sides of said body, a gripper member hingedly mounted on one side of said body and extendible over said bar element, and a latch element mounted on the other side of said body and coactable with said 75

gripper member, said transverse bar element having its ends partially turned around the side portion of said body and resiliently maintaining itself upon the body, the inner ends of said gripper member and said latch element being formed with forked portions the fingers of which encircle the sides of the flat body and straddle

the ends of said transverse bar element, and the side portions of the flat body being formed with recessed portions into which the ends of the transverse bar element engage to hold the latter against shifting.
